UNITED STATES PATENT OFFICE.

EDWARD WESTON, OF NEWARK, NEW JERSEY.

DESIGN FOR A MAGNET.

SPECIFICATION forming part of Design No. 19,896, dated June 10, 1890.

Application filed May 12, 1890. Serial No. 351,565. Term of patent 14 years.

To all whom it may concern:

Be it known that I, EDWARD WESTON, of Newark, Essex county, New Jersey, have invented and produced a new and original Design for Magnets, of which the following is a specification.

My design relates to a magnet of the so-called horseshoe form; and it consists in the novel and distinctive configuration of the magnet, substantially as herein shown.

The drawing is a perspective view of a magnet embodying my design.

The general appearance of the magnet is that of a bar having parallel sides and faces and bent to the configuration described. The

middle portion A of said bar is curved in nearly elliptical shape. From the ends of the said middle portion the parts B and C of the bar converge, and then beyond the parts B C the end portions D and E appear parallel. 20 The angles F G, between the parts B D and C E, are rounded.

I claim—

The design for a magnet, substantially as herein shown and described.

EDWARD WESTON.
